FLOCK DEPILLING MACHINE

Harold M. Ratley, Highland Park, and Alvin C. Lind, Detroit, Mich., assignors to National Automotive Fibres, Inc., Detroit, Mich., a corporation of Delaware

Application March 18, 1946, Serial No. 655,327

17 Claims. (Cl. 19—80)

1

The invention relates generally to machines for making carpet of the cemented pile type and refers more particularly to a flock depilling machine, i. e., a machine having means for breaking up balls, pills or other objectionable formations of the cut fibers so that they may be distributed downwardly in substantially free and loose condition from the machine onto the cement coated surface of the base carpet material.

It is, therefore, the primary object of the instant invention to accomplish this depilling operation.

It is a further object of the invention to perform the depilling directly above the point or points of deposit, preferably above a suitable vibrating screen through which the separated or loose fibers may be sifted onto the cement coated surface of advancing base carpet material.

With these objects in view, the invention consists in the method and apparatus as hereinafter set forth.

In the drawings:

Fig. 1 is an elevation of the depilling apparatus embodying our invention:

Fig. 2 is a plan view thereof;

Fig. 3 is a vertical longitudinal section through the right hand depilling device;

Fig. 4 is a plan view thereof partly broken away in section; and

Fig. 5 is a side elevation partly in section.

The improved method employed for depilling the flock consists essentially in passing the flock between rotary brushes which are revolving at differential peripheral speeds and in close proximity to each other. Preferably the flock is passed in a downward direction between successive pairs of such rotary brushes and is finally delivered onto a vibrating screen through which it is sifted onto the cement coated surface of the advancing carpet material to form the pile.

As illustrated in Fig. 1, the depilling mechanism is supported independently of the rest of the carpet forming machine in a position above the vibrating screen thereof. Inasmuch as the vibrating screen and means for advancing the cement coated base carpet material form no part of the present invention, we have shown in Fig. 1 dotted lines A—A to indicate the position of the vibratory screen in such machine, and dotted lines B—B to indicate the plane of travel of the cement coated carpet material.

Preferably two depilling devices are supported in parallel relation to each other upon a suitable horizontal support C which, if necessary, may be reinforced by one or more girders C'.

2

C² and C³ are vertical openings through the support C and are preferably above the vibrating screen designated by the lines A—A.

D and D' are base plates secured to the support C and surrounding the openings C² and C³, and E and E' are casings rigid with the plates D and D' and extending downwardly through the openings C² and C³ for conducting the flock to the vibrating screen aforesaid. Extending upward from each of the plates D and D' is a casing F of rectangular form. Within each casing are two adjacent vertical series of rotary brushes respectively G, G', etc., and H, H', etc. These brushes are preferably formed with wire bristles and the brushes of the G series have relatively short bristles I, while the brushes of the H series have longer bristles I'. The brushes in the two series are staggered in relation to each other so that a brush H is peripherally adjacent the two brushes G and G', and so on down through the series.

As above stated, the adjacent brushes between which the material is fed rotate at differential speeds, the slow speed being imparted to the brushes of the series G, G', etc., and the high speed to the brushes H, H', etc. Also in the latter series, the speed is progressively increased from top to bottom, as for instance, 438 R. P. M. for the top brushes in the casings F, 493 R. P. M. for the next lower brushes, and 522 R. P. M. for the next lower brushes, etc. The brushes of the other series may all be driven at the same low speed, such as 14.84 R. P. M.

Preferably the peripheral clearance between each roll in the G series and the adjacent brush in the H series is approximately .005 inch whereby the wires of the brushes in the fast rotating H series move close to the wires of the slow rotating brushes in the G series to break up pills, balls, or other formations of the fibers passing downwardly therebetween. In this connection it will be noted that the slow rotating brushes in the G series rotate anti-clockwise while the fast rotating brushes in the H series rotate clockwise whereby the adjacent peripheral portions of the brushes in said series G and H travel in the same direction to project downwardly the fibers passing therebetween.

The driving power for the brushes in each casing F preferably comprises two separate motors J and J' which are located between the two casings and are supported upon a frame K.

Each motor J is provided with a transmission J² and the driven shaft L of this transmission has a pair of pulleys L' and L² thereon connected

by belts L^3 and L^4 to pulleys M , M' for the brushes of the slow rotating series G . Preferably the belt L^3 passes around pulleys M for the two uppermost brushes G , G' , while the belt L^4 passes about pulleys M' for the lower brushes G^2 and G^3 .

Each motor J' has directly mounted on its shaft a pair of sprocket wheels N and N' . The sprocket wheel N is connected by a chain N^3 with sprocket wheels N^4 and N^5 respectively for the fast rotating brushes H and H' . The sprocket wheel N' is connected by a chain N^6 with sprocket wheels N^7 and N^8 respectively on brushes H^2 and H^3 . Preferably the speed of the brushes H , H' , H^2 and H^3 is progressively increased from top to bottom by providing each succeeding sprocket from top to bottom with a smaller number of teeth. For example, the sprocket N^6 has a smaller number of teeth than the sprocket N^4 ; the sprocket N^7 has a smaller number of teeth than the sprocket N^5 , etc.

With the construction as above described, the balls, pills, etc. of fibers such, for example, as wool fibers, are fed to each of the casings F of the depillers from the hoppers O at the upper ends thereof. As shown in Fig. 3, an adjustable gate P is provided within each casing F to regulate the quantity of fibers adapted to pass from the slow rotating upper brush G to the fast rotating upper brush H . The wires of the brush H will move close to the wires of the slow rotating brush G to initially break up pills, balls or other formations of the fibers supplied thereto. Thus, the bristles I' will separate some of the fibers of the pills but will yield to permit passage of tangled portions not fully untangled. The process will be repeated in passing the material downwardly between the brushes H and G' which produce further separation, and so on down until after discharge from the lowermost brushes G^3 and H^3 . The completely separated individual fibers will be discharged by the lowermost brushes G^3 and H^3 downward through the casings E and E' onto the vibratory screen represented by the line A — A to be sifted by said screen onto the cement coated surface of the advancing base material represented by the line B — B .

What we claim as our invention is:

1. A machine for depilling flock comprising a casing, two adjacent vertical series of rotary brushes within said casing, the brushes of one series having longer bristles than the brushes of the other series and the adjacent peripheral portions of the brushes in the two series being in close proximity and traveling in the same direction, means for feeding the flock into said casing above the uppermost of said short bristle brushes, and means for rotating the brushes of the two series differentially comprising two motors having their driven shafts rotating respectively at low and at high speeds, a pulley and belt transmission between the low speed motor and the brushes having the short bristles, a sprocket and chain transmission between the high speed motor and the brushes having the long bristles, the sprockets for the successive brushes having progressively fewer teeth to drive the same at progressively higher speeds.

2. A machine for depilling flock comprising a supporting frame, a plurality of casings mounted in spaced relation on said frame, two adjacent vertical series of rotary brushes within each of said casings, the brushes of one series having longer bristles than the brushes of the other series and the adjacent peripheral portions of the brushes in the two series being in close proximity

and traveling in the same direction, means for feeding flock into each of said casings above the uppermost of said lower speed brushes, and means for rotating the brushes of the two series differentially comprising pairs of motors adjacent to each of said casings, one motor of each pair having its driven shaft rotating at relatively low speed, a transmission between said low speed motor and the series of brushes having the shorter bristles, and a transmission connection between the high speed motor and the brushes having the longer bristles operable to rotate the latter at progressively higher speeds.

3. A machine for depilling flock comprising a supporting frame, a plurality of casings mounted in spaced relation on said frame, two adjacent vertical series of rotary brushes within each of said casings, the brushes of one series having longer bristles than the brushes of the other series and the adjacent peripheral portions of the brushes in the two series being in close proximity and traveling in the same direction, means for feeding flock into each of said casings above the uppermost of said lower speed brushes, and means for rotating the brushes of the two series differentially comprising two motors adjacent to each of said casings and having their driven shafts rotating respectively at low and at high speeds, a pulley and belt transmission between the low speed motor and the brushes having the short bristles, a sprocket and chain transmission between the high speed motor and the brushes having the long bristles, the sprockets for the successive brushes having progressively fewer teeth to drive the same at progressively higher speeds, and means connected to the lower end of each of said casings for discharging the material therefrom at spaced positions in relation to a carpet forming machine.

4. A machine for depilling flock comprising a casing, two series of rotary brushes within said casing, the brushes of each series having wire bristles and being in vertical alignment, the brushes of one series being arranged in staggered relation to the brushes of the other series with a predetermined clearance between the peripheral portions of the brushes in the two series, the brushes of one series rotating oppositely to the direction of rotation of the brushes of the other series whereby adjacent peripheral portions of the brushes in said two series travel in the same direction to project downwardly the flock passing therebetween, means for rotating the brushes in the two series at differential speeds, the rate of rotation of the brushes of one series being progressively increased from top to bottom of said series, and means for feeding flock into the casing so that it will pass successively between the staggeredly arranged differentially rotating brushes.

5. An apparatus for depilling flock having two adjacent vertical series of rotary brushes, the brushes of one series rotating at low speed, the brushes of the other series rotating at relatively high speed, the brushes of the two series being in staggered relation to each other with the brushes of low speed uppermost whereby a high speed brush is peripherally adjacent two low speed brushes, the brushes of low speed having relatively short radially extending bristles, the brushes of high speed having longer bristles, the rate of rotation of the high speed brushes being progressively increased from top to bottom of the series, the peripheral clearance between the brushes of low speed and the adjacent brushes

of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween.

6. An apparatus for depilling flock having two adjacent vertical series of rotary brushes, the brushes of one series rotating at low speed, the brushes of the other series rotating at relatively high speed, the brushes of the two series being in staggered relation to each other with the brushes of low speed uppermost whereby a high speed brush is peripherally adjacent two low speed brushes, the brushes of low speed having relatively short radially extending bristles, the brushes of high speed having longer bristles, the rate of rotation of the high speed brushes being progressively increased from top to bottom of the series, the peripheral clearance between the brushes of low speed and the adjacent brushes of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween, means for feeding flock to be depilled onto the uppermost low speed brush to be carried thereby to the uppermost high speed brush, and means adjacent the uppermost low speed brush for regulating the quantity of flock to pass therefrom to the uppermost high speed brush.

7. An apparatus for depilling flock having two adjacent vertical series of rotary brushes, the brushes of one series rotating at low speed, the brushes of the other series rotating at relatively high speed, the brushes of the two series being in staggered relation to each other with the brushes of low speed uppermost whereby a high speed brush is peripherally adjacent two low speed brushes, the brushes of low speed having relatively short radially extending bristles, the brushes of high speed having longer bristles, the rate of rotation of the high speed brushes being progressively increased from top to bottom of the series, the peripheral clearance between the brushes of low speed and the adjacent brushes of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween, and means for feeding flock to be depilled onto the uppermost low speed brush to be carried thereby to the uppermost high speed brush.

8. An apparatus for depilling flock having two adjacent vertical series of rotary brushes, the brushes of one series rotating at low speed, the brushes of the other series rotating at relatively high speed, the brushes of the two series being in staggered relation to each other with the

brushes of low speed uppermost whereby a high speed brush is peripherally adjacent two low speed brushes, the brushes of low speed having relatively short radially extending bristles, the brushes of high speed having longer bristles, the rate of rotation of the high speed brushes being progressively increased from top to bottom of the series, the peripheral clearance between the brushes of low speed and the adjacent brushes of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween, means for feeding flock to be depilled onto the uppermost low speed brush to be carried thereby to the uppermost high speed brush, and means adjustable relative to the uppermost low speed brush for regulating the quantity of flock to pass therefrom to the uppermost high speed brush.

9. An apparatus for depilling flock having two adjacent vertical series of rotary brushes, the brushes of one series rotating at low speed, the brushes of the other series rotating at relatively high speed, the brushes of the two series being in staggered relation to each other with the brushes of low speed uppermost whereby a high speed brush is peripherally adjacent two low speed brushes, the rate of rotation of the high speed brushes being progressively increased from top to bottom of the series, the peripheral clearance between the brushes of low speed and the adjacent brushes of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween.

10. An apparatus for depilling flock having two adjacent vertical series of rotary brushes, the brushes of one series rotating at low speed, the brushes of the other series rotating at relatively high speed, the brushes of the two series being in staggered relation to each other with the brushes of low speed uppermost whereby a high speed brush is peripherally adjacent two low speed brushes, the peripheral clearance between the brushes of low speed and the adjacent brushes of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween.

11. An apparatus for depilling flock having two adjacent vertical series of rotary brushes, the brushes of one series rotating at low speed, the brushes of the other series rotating at relatively high speed, the brushes of the two series being in staggered relation to each other with the brushes of low speed uppermost whereby a high speed brush is peripherally adjacent two low

speed brushes, the rate of rotation of the high speed brushes being progressively increased from top to bottom of the series, the peripheral clearance between the brushes of low speed and the adjacent brushes of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween, and means for feeding flock to be depilled onto the uppermost low speed brush to be carried thereby to the uppermost high speed brush.

12. An apparatus for depilling flock having two adjacent vertical series of rotary brushes, the brushes of one series rotating at low speed, the brushes of the other series rotating at relatively high speed, the brushes of the two series being in staggered relation to each other with the brushes of low speed uppermost whereby a high speed brush is peripherally adjacent two low speed brushes, the rate of rotation of the high speed brushes being progressively increased from top to bottom of the series, the peripheral clearance between the brushes of low speed and the adjacent brushes of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween, means for feeding flock to be depilled onto the uppermost low speed brush to be carried thereby to the uppermost high speed brush, and means adjacent the uppermost low speed brush for regulating the quantity of flock to pass therefrom to the uppermost high speed brush.

13. An apparatus for depilling flock having two adjacent vertical series of rotary brushes, the brushes of the two series being in staggered relation to each other with the brushes of one series uppermost whereby a brush of the other series is peripherally adjacent two brushes of the first mentioned series, the rate of rotation of the brushes of one series being progressively increased from top to bottom of said series, the brushes of both series having radially extending bristles, the peripheral clearance between the brushes of one series and the adjacent brushes of the other series being relatively small whereby the bristles of the brushes of said one series move close to the bristles of the brushes of said other series to break up pills, balls or other fromations of the flock, the brushes of one series rotating oppositely to the direction of rotation of the brushes of the other series whereby adjacent peripheral portions of the brushes in said two series travel in the same direction to project downwardly the flock passing therebetween.

14. An apparatus for depilling flock having two adjacent vertical series of rotary brushes, the brushes of the two series being in staggered relation to each other with the brushes of one series uppermost whereby a brush of the other series is peripherally adjacent two brushes of the first mentioned series, the rate of rotation of the brushes of one series being progressively in-

creased from top to bottom of said series the brushes of both series having radially extending bristles, the peripheral clearance between the brushes of one series and the adjacent brushes of the other series being relatively small whereby the bristles of the brushes of said one series move close to the bristles of the brushes of said other series to break up pills, balls or other formations of the flock, the brushes of one series rotating oppositely to the direction of rotation of the brushes of the other series whereby adjacent peripheral portions of the brushes in said two series travel in the same direction to project downwardly the flock passing therebetween, means for feeding flock to be depilled onto the uppermost brush of the first mentioned series to be carried thereby to the uppermost brush of said other series, and means adjacent the uppermost brush of said first mentioned series for regulating the quantity of flock to pass therefrom to the uppermost brush of said other series.

15. Apparatus for depilling flock having an upright casing of substantially rectangular form open at the top and bottom thereof, two adjacent vertical series of rotary brushes within said casing between the open top and bottom thereof, the brushes of one series rotating at low speed, the brushes of the other series rotating at relatively high speed, the brushes of the two series being in staggered relation to each other with the brushes of low speed being uppermost, the brushes of both series having radially extending bristles, the peripheral clearance between the brushes of low speed and the adjacent brushes of high speed being relatively small whereby the bristles of the brushes of high speed move close to the bristles of the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween and means for feeding flock to be depilled onto the uppermost low speed brush to be carried thereby to the uppermost high speed brush, including a hopper directly above and discharging onto the uppermost brush of the low speed series, and an adjustable gate within said casing adjacent said uppermost brush of the low speed series to regulate the quantity of flock adapted to pass from said uppermost brush of the low speed series to the uppermost brush of the high speed series.

16. Apparatus for depilling flock having an upright casing open at the top and bottom thereof, two adjacent vertical series of rotary brushes within said casing between the open top and bottom thereof, the brushes of one series rotating at low speed, the brushes of the other series rotating at relatively high speed, the brushes of the two series being in staggered relation to each other with the brushes of low speed being uppermost, the peripheral clearance between the brushes of low speed and the adjacent brushes of high speed being relatively small whereby the brushes of high speed move close to the brushes of low speed to break up pills, balls or other formations of the flock, the brushes of high speed rotating oppositely to the direction of rotation of the brushes of low speed whereby adjacent peripheral portions of the brushes in said two series travel in the same direction to project downwardly the flock passing therebetween, and means for feeding flock to be depilled onto the

uppermost low speed brush to be carried thereby to the uppermost high speed brush.

17. Apparatus for depilling flock having an upright casing open at the top and bottom thereof, two adjacent vertical series of rotary brushes within said casing between the open top and bottom thereof, the brushes of the two series being in staggered relation to each other with the brushes of one series uppermost whereby a brush of the other series is peripherally adjacent two brushes of said one series, the rate of rotation of the brushes of said other series being progressively increased from top to bottom of said series, the brushes of one series rotating oppositely to the direction of rotation of the brushes of the other series whereby adjacent peripheral portions of the brushes in said two series travel in the same direction to project down-

wardly the flock passing therebetween, and means for feeding flock to be depilled onto the uppermost brush of said one series to be carried thereby to the uppermost brush of said other series.
